Application July 9, 1938, Serial No. 218,310

17 Claims. (Cl. 250—17)

Our invention relates to generators for electrical oscillations and particularly to such generators in which a magnetic field is employed to traverse the electron path between the anode and the cathode.

One object of our invention is to provide an electrical generator of the above-mentioned type which is particularly adapted to generate ultra high frequency currents.

Another object of our invention is to provide a generator of the type described above in which the electrical circuit elements are symmetrically disposed relative to the tube axes.

Another object of our invention is to provide an electric generator which has a natural frequency, or plurality of frequencies, of electrical vibration; in other words, the generator has a plate structure which constitutes in itself an oscillatory circuit having uniformly distributed inductance and capacity which fixes the generated frequency.

Still another object of our invention is to provide an electrical discharge tube in which the output can be varied by varying a magnetic field traversing the electron paths between the anode and cathode thereof.

Still another object of our invention is to provide an electrical generator, the output of which can be varied at will and in substantially instantaneous response to the fluctuations of a controlling magnetic field, or of the anode potential.

Other objects of our invention will become apparent upon reading the following description in which:

Figure 1 is a view partly in cross section and partly in elevation of a tube embodying the principles of our invention, together with schematically diagrammed electrical circuits for using the same.

Fig. 2 is a cross sectional view taken on the line II—II of Fig. 1.

Fig. 3 is a diagram used in explaining the principles of our invention.

Fig. 4 is a view of the same type as Fig. 1 of a modified form of our invention;

Fig. 5 is a view of a portion of the tube of Fig. 1 arranged with a modified form of antenna connection; and

Fig. 6 is a detailed view, partly in cross-section, of a tuning means employed in the tube of Fig. 1.

Referring particularly to Figure 1, a vacuum-tight enclosure 1 which may be of glass, quartz or other suitable material, and which is preferably made in the form of an elongated cylinder, 55 has reentrant stems 2, 3 at its respective ends

through which are sealed in-leading wires which support electron emissive cathodes 4, 5 which may suitably be of the thermionically emissive type. A cylindrical metallic electrode 6 may be supported by an in-leading wire 7 and is preferably made coaxial with the enclosure 1. The two cathodes 4 and 5 may be made to project by approximately equal distances which may be comparatively short inwardly from each end of the cylinder 6. Also extending inward from each end of the cylinder 6 is a pair of diametrically opposite slots 8, 9, 10, 11. The slots 8, 9, 10, 11 preferably extend equal distances inward from their respective ends of the cylinder 6, and may extend so far as to leave only a narrow connecting bridge 12 at substantially the midpoint of the latter. The supporting in-lead 7 is likewise attached to the cylinder 6, preferably at its midpoint. At two points which are preferably spaced equally distant from the midpoint of the cylinder 6, connecting leads 13, 14 are sealed through the enclosure 1, and extensions of these leads form a transmission line for conveying the output of tube 1 to any load circuit such as a single antenna or a pair of antennae 15, 16 which are preferably each of the same length as the cylinder 6. Alternatively, however, either antenna 15 or 16 may be N times the length of the electrode 6 where N is any integer. We prefer to provide means such as the two solenoids 17, 18 for producing a magnetic field parallel to the axis of the anode cylinder 6. We may provide means at 19 and 20 by which the magnetic field in the region of each cathode 4 may be adjusted. The source of current 21 which energizes the magnets 17 and 18 should be of the continuous (i. e., direct) current type.

To energize the two cathodes 4 and 5, we provide a pair of circuits 22, 23 which are preferably provided with tuning means such as the reflecting bridges 24 and 25 for imparting to that portion of either of them which is traversed by high-frequency currents an electrical length which is approximately equal to that of cylinder 6. One suitable arrangement for so tuning the circuits 22, 23 is to make the leads adjacent the seals at each end of the container 1 in the form of a concentric transmission line shown in detail in Fig. 6; that is to say, in the form of a tube 27 with a conducting core 28 in its axis, and to provide this tube with a telescoping end portion 24 which slides upon the core 28 and is insulated from tube 27 by an insulating film and which may be moved in and out so as to make the electrical length intervening between the respective fila- 50 55

ment 4 or 5 and the outer end of said tube approximately one-half the wave length pointed out below as characterizing the electrical vibration of anode cylinder 6. To supply operating energy 5 producing current flow between the cylinder 6 and the two cathodes 4 and 5, we connect an electrical source of current 26 between the leads 7 and the two telescoping ends, or other half wave points, on the respective input circuits supplying current to the cathodes 4 and 5. We may provide a variable impedance 27 so that the output of source 26 may be controlled. The source 26 should be of the continuous (i. e., direct) current type with its positive terminal connected 10 to the lead 7. As a particularly convenient and desirable arrangement, we may connect the negative lead from the source 26 to ground and may also ground the telescoping collars or other half-wave points on the above described circuits 15 which supply current to the cathodes 4 and 5.

The reference numerals in Fig. 2 apply to the same structural elements as do the similar reference numerals in Fig. 1, and Fig. 2 is accordingly believed to require no separate explanation.

25 Upon energizing the sources 21 and 26 and bringing the cathodes 4 and 5 up to incandescence, it will be found that the above described system will generate electrical oscillations having a wave length equal to approximately twice 30 the length of cylinder 6. In other words, the electrical potential distributions of the cylinder 6 will be as indicated symbolically in Fig. 3 where the dotted curve represents one instantaneous value of electrical potential varying from point 35 to point along the length of cylinder 6, the axis of said cylinder constituting the zero for ordinates of the curve. Since the length of cylinder 6 may obviously be made relatively small, the apparatus which we have described is capable 40 of generating electrical oscillations of relatively short wave length.

While we have shown the leads 13, 14 as connected to two separate antennae, it will be recognized that the latter are merely symbolical of 45 any form of tunable electrical systems adapted to respond to oscillations of a wave length equal to twice the length of the cylinder 6.

It will be noted that the above described arrangement provides a very simple, rugged and 50 inexpensive arrangement for generating ultra high frequency electrical vibrations, and for modulating them at will, and that it is symmetrical relative to the midpoint of the enclosure 1 and is adapted by arrangement in a horizontal position to be made symmetrical relative to the earth and its surroundings.

As a specific illustration of one embodiment of our invention, the tube 1 in Fig. 1 may be of glass $1\frac{1}{2}$ inches in diameter and 4 inches in 60 overall length. The cathodes 4 and 5 may each consist of tungsten wire .005 inch in diameter and $\frac{1}{2}$ inch in length between the ends of the heated portion. The tube 1 should be evacuated to the highest vacuum which is practicable, and 65 under these conditions, the cathodes 4, 5 will require approximately 3 amperes at 1.5 volts to raise them to a proper operating temperature. The cylindrical anode 6 may have an overall length of $1\frac{1}{2}$ inches and be $\frac{1}{2}$ inch in outside 70 diameter and .2 inch in inside diameter. The slot 8 may be $\frac{1}{16}$ inch wide and the bridge-portion 12 may be $\frac{1}{8}$ inch in length in an axial direction. The concentric transmission lines for carrying a heating current to the cathodes 4 and 75 5 may each comprise a cylinder of copper tubing

approximately 8 inches long and having a wall $\frac{1}{2}$ inch thick, together with a central core of copper wire about $\frac{1}{2}$ inch in diameter. The magnetizing windings 17 and 18 may consist of approximately 11000 turns of insulated copper 5 wire of #24 enameled copper, and the source 21 should be of such size that it can supply a current of .25 ampere to each said winding. The source 26 should be able to supply .020 ampere at 1500 volts to operate the tube.

10 Fig. 4 shows a modification of the tube embodying our invention which differs from Fig. 1 in that its cathode consists of a single filament 31 extending along the axis of the anode cylinder 6 from one end of the latter to the other. 15 The separate sources of heating current 22 and 23 of Fig. 1 are accordingly replaced by a single source 32 which may conveniently be the secondary of a transformer connected to an alternating-current source. With this arrangement, 20 there is, of course, no occasion for the employment of the tuning bridges 24, 25. The negative terminal of the direct-current source 26 and its associated resistor 27 are then connected to the midpoint of the transformer secondary 32. If 25 desired, said midpoint may be connected to ground.

Since otherwise the circuit connections and structure of the tube of Fig. 4 are similar to those of Fig. 1, the remaining structural elements need no separate description, but are designated by the same reference numerals as corresponding elements in Fig. 1.

In Fig. 5 is shown a modified way of connecting the antennae or output circuit for the tubes 35 of either Fig. 1 or Fig. 4. The respective antennae 33 and 34, each equal in length to anode cylinder 6, are connected to two points on opposite sides of the slot 10 (or 8) in anode 6, said points preferably being each distant from the 40 midpoint of anode 6 by a distance adjusted in operation in accordance with well-known practice in the radio and telephone arts so as to match the load impedance to the tube impedance. The leads 35 and 36 form a transmission 45 line to convey the output from anode 6 to antennae 33 and 34.

While we have described a particular embodiment of our invention, the principles thereof are capable of broad application which will be obvious to those skilled in the art. We accordingly desire that the following claims shall be given the broadest construction by which their terms are susceptible of limitations made necessary by the prior art.

55 We claim as our invention:

1. In combination, a vacuum-tight enclosure, a pair of electron sources displaced from each other therein, means to produce a magnetic field along the line connecting said electron sources, a co-operating electrode comprising two hemi-cylinders having their axes substantially coincident with said line, at least one antenna having a length which is N times the length of said co-operating electrode connected to the latter, where 60 N is any integer, a source of electric power connected to substantially the midpoint of said co-operating electrode, a power supply having leads for each said electron source and means to tune a portion of the leads therefrom to a wave-length 65 which is twice the length of said co-operating electrode, and means to connect said source to two points on said leads which are electrically distant from their associated electron sources by the length of said co-operating electrode.

- 5 nected to substantially the midpoint of said co-
operating electrode, a power supply having leads
for each said electron source and means to tune
a portion of the leads therefrom to a wave length
which is twice the length of said cooperating
electrode, and means to connect said source to
two points on said leads which are electrically
distant from their associated electron sources
by the length of said cooperating electrode.
- 10 11. In combination, a vacuum-tight enclosure,
a pair of electron sources displaced from each
other therein, means to produce a magnetic field
along the line connecting said sources, a cooper-
ating electrode in the form of a cylinder the
15 axis of which coincides with said line and which
has a pair of diametrically opposite slits ex-
tending toward its midpoint from each of its
ends, at least one antenna having a length which
is N times the length of said cooperating elec-
trode, where N is any integer, connected to the
20 latter, a source of electric power connected to
substantially the midpoint of said cooperating
electrode, a power supply having leads for each
said electron source and means to tune a por-
tion of the leads therefrom to a wave length
25 which is twice the length of said cooperating
electrode, and means to connect said source to
two points on said leads which are electrically
distant from their associated electron sources by
30 the length of said cooperating electrode.
12. In combination, a vacuum-tight enclosure,
a pair of electron sources displaced from each
other therein, means to produce a magnetic field
along the line connecting said sources, a cooper-
ating electrode in the form of a cylinder the
35 axis of which coincides with said line and which
has a pair of diametrically opposite slits extend-
ing toward its midpoint from each of its ends,
a source of electric power connected to substan-
tially the midpoint of said cooperating electrode,
40 a power supply having leads for each said elec-
tron source and means to tune a portion of the
leads therefrom to a wave length which is twice
the length of said cooperating electrode, and
45 means to connect said source to two points on
said leads which are electrically distant from
their associated electron sources by the length
of said cooperating electrode.
13. In combination, a vacuum-tight enclosure,
50 a pair of electron sources displaced from each
other therein, means to produce a magnetic field
along the line connecting said sources, a cooper-
ating electrode in the form of a cylinder the
55 axis of which coincides with said line and which
has a pair of diametrically opposite slits extend-
ing toward its midpoint from each of its ends,
at least one antenna having a length which is
N times the length of said cooperating electrode connected, where N is any integer, to the latter at points equidistant from its midpoint, a source of electric power connected to substantially the midpoint of said cooperating electrode, a power supply having leads for each said electron source and means to tune a portion of the leads therefrom to a wave length which is twice the length of said cooperating electrode, and means to connect said source to two points on said leads which are electrically distant from their associated electron sources by the length of said cooperating electrode.
14. In combination, a vacuum-tight enclosure,
a pair of electron sources displaced from each
other therein, means to produce a magnetic field
along the line connecting said sources, a cooper-
ating electrode in the form of a cylinder the
15 axis of which coincides with said line and which
has a pair of diametrically opposite slits extend-
ing toward its midpoint from each of its ends,
a source of electric power connected to substan-
tially the midpoint of said cooperating electrode,
20 a power supply for each said electron source
supplying the latter through a concentric-type
transmission line comprising a concentric rod
and cylinder having tuning means comprising a
reflecting bridge, and means to connect said
25 source to each of said reflecting bridges.
15. In combination, a vacuum-tight enclosure,
a pair of electron sources displaced from each
other therein, means to produce a magnetic field
along the line connecting said sources, a cooper-
ating electrode in the form of a cylinder the
30 axis of which coincides with said line and which
has a pair of diametrically opposite slits extend-
ing toward its midpoint from each of its ends,
two antennae having wave lengths which are of
the length of said cooperating electrode and
35 which are connected to the latter respectively at
two points equally distant from its midpoint,
a source of electric power connected to substan-
tially the midpoint of said cooperating electrode,
a power supply for each said electron source sup-
plying the latter through a concentric-type trans-
40 mission line comprising a concentric rod and
cylinder having tuning means comprising a re-
flecting bridge, and means to connect said source
to each of said reflecting bridges.
16. The arrangement specified in claim 14 but
having the terminal of said source which is
nearest to said cathodes grounded.
17. The arrangement specified in claim 15 but
having the terminal of said source which is
nearest to said cathodes grounded.

55
